Axinn Veltrop Harkrider LLP(57) **CLAIM**

The ornamental design for a laser processing head, as shown and described.

DESCRIPTION

FIG. 1 is a front top right perspective view of a laser processing head showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is a front right elevation view thereof.

The broken lines in the drawings depict unclaimed environmental subject matter.
